UNITED STATES PATENT OFFICE.

FRANK W. LEWIS, OF McLEOD, MONTANA.

AMALGAMATOR.

1,034,259.

Specification of Letters Patent. Patented July 30, 1912.

Application filed August 19, 1910. Serial No. 577,991.

To all whom it may concern:

Be it known that I, FRANK W. LEWIS, a citizen of the United States of America, residing at McLeod, in the county of Sweet

5 Grass and State of Montana, have invented new and useful Improvements in Amalgamators, of which the following is a specification.

This invention relates to amalgamators of 10 that class in which the process of pulverizing the ore is completed during the process of amalgamation in order to insure a perfect separation of the metal, and it has particular reference to that class of ore pulverizing 15 amalgamators in which a cylinder mounted for rotation is provided with interiorly disposed riffles, ore grinding or comminuting members such as rocks or boulders being placed within the cylinder to be elevated by 20 the rotation thereof and to be dropped with crushing force upon the ore contained in or passing through said cylinder.

The principal object of the present invention is to improve the construction of the 25 riffles within the cylinder, said riffles being composed of detachable rings of peculiar construction which may be conveniently placed within the cylinder in such a manner as to be readily removed for replacement or 30 renewal when desired.

A further object of the invention is to 35 specifically improve the construction of the riffles in such a manner as to strengthen and reinforce the same to resist the impact of the grinding or crushing members, and also 40 to provide said riffles with flat anvil faces between which and the comminuting members the particles of ore passing over said faces will be crushed and ground with required degree of fineness.

With these and other ends in view which will readily appear as the nature of the invention is better understood, the same consists in the improved construction and novel 45 arrangement and combination of parts which will be hereinafter fully described and particularly pointed out in the claim.

In the accompanying drawing has been 50 illustrated a simple and preferred form of the invention, it being, however, understood that no limitation is necessarily made to the precise structural details therein exhibited, but that changes, alterations and modifications within the scope of the claim may be 55 resorted to when desired.

In the drawing,—Figure 1 is a longitu-

dinal sectional view of an amalgamator constructed in accordance with the invention. Fig. 2 is a transverse sectional view taken on the line 2—2 in Fig. 1.

60

Corresponding parts in both figures of the drawing are denoted by like characters of reference.

The shell or casing of the improved amalgamator consists of a cylindrical tube 1 made 65 preferably of steel and of any suitable dimensions, say about six feet in length by two feet in diameter. The tube is provided at its receiving and discharge ends with heads 2, 3 suitably connected therewith and 70 provided respectively with an inlet 4 and an outlet 5, said inlet and outlet being surrounded by guard flanges 6, 7. The outlet is also provided with a screen or strainer 8.

The casing contains a plurality of riffles 75 formed by rings C, each of which consists of an integral casting, said rings or castings being of an exterior diameter equal to the interior diameter of the cylindrical casing wherein said rings or castings are loosely 80 fitted so that they may be readily inserted or removed, as occasion may require. These rings or castings may be described as being of V-shaped cross section, each comprising an interior annular rim or head 9 having a 85 flat surface constituting an anvil face 9' which is parallel to and concentric with the axis of the casing, and divergent flanges 10—10 which extend outwardly from the rim or head and which are slightly curved, 90 it being noted that the rim or head portion of each ring or casting is of a thickness materially exceeding that of the flanges 10, thus insuring a durable and wear-resisting construction. The outer edges of the flanges 95 10 are formed with flat faces 10' which lie at right angles to the axis of the cylindrical casing for the convenient insertion between said faces of annular washers or gaskets 11 of rubber or other suitable compressible material, whereby tight joints will be formed 100 between the individual rings or castings.

It will be observed that the proximate flanges of adjacent rings or castings combine to form annular grooves or riffles 12 105 which in cross section may be described as being of ovate acuminate shape which has been found very effective in retaining the amalgam and in assisting the reduction of ore, as will be presently described. Any 110 desired number of rings or castings may be employed, said castings being retained with-

in the shell or casing by means of the heads when the latter are placed in position. By removing the head at either end of the casing, the contents of the casing may be removed.

The casing is supported for rotation upon a suitable frame structure 13, and it rests upon anti-friction rollers 14 which are mounted in said frame structure in any suitable and convenient manner. The shell or casing is also provided with a driving wheel 15 which may be driven by means of a belt from any suitable source of power, or said driving wheel may be in the nature of a gear wheel adapted to mesh with a pinion upon a suitably driven shaft. A feed chute 16 is directed into the feed opening 4 in the head 2 of the casing.

In the operation of this device quick silver or prepared amalgam is placed in the riffles, together with a quantity of flint boulders which have been found effective in assisting the reduction of the ore. The pulp is fed over the chute 16, and the casing is revolved at suitable speed, causing the pulp to pass therethrough, the pulp being in its passage subjected to the triturating action of the boulders, whereby it is further reduced or comminuted so as to admit of the particles of gold amalgamating with the quick silver or prepared amalgam. It will be observed that the inner faces 9' of the rims or heads 9 will form flat surfaces of relatively great width which will effectively coöperate with the boulders dropping thereupon as the cylindrical casing is rotated to crush and reduce the particles of ore pass-

ing over said rims. The pulp passes through the cylindrical casing from groove to groove and is eventually permitted to escape through the discharge aperture, the screen of which will prevent the triturating boulders from passing.

The invention as will be seen from the foregoing is very simple in construction, and it has been found to be very effective for the purposes for which it is provided.

Having thus described the invention, what is claimed as new, is:-

In an amalgamator, the combination with a cylindrical shell or casing supported for rotation and provided with heads having, respectively, an inlet and an outlet, of a plurality of riffle-forming rings fitted in said casing between the heads thereof, each ring consisting of a single casting of V-shaped cross section having an inner relatively thick rim or head having a flat face disposed in parallel relation to the axis of the cylindrical casing, and relatively thin outwardly diverging flanges slightly curved and having terminal flat faces disposed in planes at right angles to the axis of the cylindrical casing, and compressible gaskets interposed between the flat meeting faces of the flanges of the individual rings or castings.

In testimony whereof I affix my signature in presence of two witnesses.

FRANK W. LEWIS.
